LEWIS W. BRANDER AND CHARLES U. SURNER, OF CONCORD, NORTH CAROLINA; SAID SURNER ASSIGNOR TO SAID BRANDER.

JACQUARD MECHANISM FOR LOOMS.

1,158,782.

Specification of Letters Patent.

Patented Nov. 2, 1915.

Application filed October 3, 1914. Serial No. 864,748.

To all whom it may concern:

Be it known that we, LEWIS W. BRANDER and CHARLES U. SURNER, citizens of the United States, and residents of Concord, county of Cabarrus, and State of North Carolina, have invented an Improvement in Jacquard Mechanism for Looms, of which the following is a specification.

This invention relates to jacquard mechanism for looms, and consists of certain improvements which are fully set forth in the following specification and shown in the accompanying drawings which form a part thereof.

15 The invention has as one object to provide a jacquard head wherein each hook is separately connected to certain threads of the harness for governing certain warp ends whereby the neck cord, or connection between each hook and its harness, is maintained under tension for the purpose of minimizing the wear and obviating constant replacement of neck cords.

20 It has as a further object to provide a construction wherein the level of the warp is maintained substantially uniform and the tension upon the warp equalized.

25 It has as a further object to provide a harness movement which affords a full open shed at predetermined times and by means of which the tension upon the warp is materially lessened whereby in the operation of the head the number of broken warp ends is greatly reduced in the cycle of operations.

30 It has as a further object to provide a construction wherein an increased number of hooks may be employed as compared to prior jacquard heads of substantially the same size, thereby reducing the number of 35 cards while correspondingly increasing the field and scope of design.

40 It has for a further object to provide a jacquard mechanism, the cards of which operate substantially simultaneously in pairs, 45 each pair representing together one pick of the weft, so that in punching the cards one card is punched to form one portion of the pick and another card the remaining portion of the same pick.

50 Referring to the drawings:—Figure 1 represents a diagrammatic sectional elevation of a jacquard head embodying our invention; Fig. 2 represents a side elevation

of the head and certain of its operating adjuncts; Fig. 3 represents a plan of the stationary frame for supporting the needle rack; Fig. 4 represents diagrammatically the warp slid in operative position; Fig. 5 represents a perspective of a portion of the movable grate which forms a support for the hooks; Fig. 6 represents a perspective of a modified form of griff frame; and Fig. 7 represents a detail of one of the supports for the brace rack for the needles.

Similar numerals of reference indicate corresponding parts.

1 designates the head frame of a jacquard mechanism embodying our invention and in the present instance is the usual type of head for a double cylinder, double lift machine 70 which we have preferred to employ as the foundation about which the construction of our invention is formed.

2 and 3 designate respectively the cylinders about which the cards 4 pass in the 75 usual manner, and each cylinder is connected at its ends to the movable rods 5 which are guided in suitable lugs 6 of the frame and serve to move the cylinders toward and away from the cylinder plates 7, these latter 80 supporting the outer ends of the sets of needles 8. In the present construction the two cylinders are brought into operative relation in close proximity to the cylinder plates simultaneously instead of alternately 85 as is the ordinary practice in a double lift machine, and the mechanism for actuating the cylinders consists of a pair of arms 9 for each cylinder and which are so shaped as to form a cam guideway for the respective 90 cam rollers 10. The cam rollers 10 are carried respectively by the arms 11, which in turn are fixed in any suitable manner to the reciprocable plunger rods 12 and 13. These rods are mounted in pairs for sliding 95 movement in apertured brackets or bearing lugs 14 of the frame 1 and receive their movement through mechanism which will be later described. It will be understood that there is a plunger rod 12 at each side of 100 the machine which is not only connected to the adjacent arm 11 but is also fixed to a sleeve or lug of the part 15 of the upper griff frame. In a similar manner there is a plunger rod 13 at each side of the machine, said rods being fixed respectively to

105

the lower movable part 16 of the upper griff frame.

17 designates pins corresponding in number to the arms 11, one being secured to each 5 arm and extending laterally to receive and form a pivot for a socket member 18, each of which has threaded connection with a rod 19, the outer ends of which are threaded into a head 20. Thus at each side of the 10 machine there is one head connected to two of the rods 19, while the heads in turn are pivoted respectively to the ends of the bifurcated beam lever 21. This lever 21 is fulcrumed at 22 upon a suitable support 23 and 15 receives its motion through the long arm 24 driven by a crank or like motion from a suitable part of the loom mechanism.

From the foregoing it will be apparent that a rocking movement of the beam 21 causes both parts 15 and 16 of the upper griff frame to be simultaneously raised or simultaneously lowered according to the direction of movement of the beam and thereby moves all of the knives 25 and 26 of the 20 upper griff frame simultaneously and in the same direction. These knives or griffs serve as supports and carriers for the hooks 27, and each hook is controlled by a needle 8 in the well known manner. The lower ends of 25 the hooks pass respectively through slots or apertures 28 of the grate or auxiliary griff frame 29, and are reversely turned to form a hook 30 at the lower end which is adapted to seat upon the transverse supports 31 of the 30 grate, this construction being well understood to those skilled in the art. The grate or auxiliary griff frame 29 in the present instance is formed in sections, all of which are held by the end plates 32, which are 35 clamped together by the bolts 33 or like securing means. By forming the grate in sections it is a comparatively easy matter to replace a broken section as it is unnecessary in this construction to disturb the entire tie-up as is required where an entire grate must be replaced.

As here shown, the grate or auxiliary griff frame 29 is movably mounted within the frame 1 in such a manner that it is free 40 to reciprocate and therefore forms a movable support for the lower extremities of the hooks 27, the arrangement being such that the grate moves down while the griff frames are moving up and vice versa. Consequently 45 those hooks which are not called up by the cards for a pick are lowered with the grate. In this connection it will be noted that the weight of the harness 34 and the lingoies 35 is sufficient to drop the hooks by gravity as 50 the grate moves downwardly. In order to cause the proper movement of the grate or auxiliary griff frame 29 in timed relation with the movable griff frames, we have provided at each side of the grate a sleeve 36 55 fixed thereto in any suitable manner and

mounted for sliding movement upon the rods 12. The sleeves 36 in turn are connected respectively to rock levers 37 through the medium of links 38, said levers each being pivoted at 39 to a fixed support 40 and 60 connected at one end by a turn-buckle 41 to the beam 21. It will therefore be apparent that rocking movement of the beam 21 will cause the upper and lower griff frames to be simultaneously reciprocated in unison while 65 the grate 29 will be reciprocated oppositely, thus causing certain of the hooks to be raised while the remaining hooks are lowered so that the opening of the shed is formed by certain of the warp ends being 70 raised while the remaining warp ends are lowered. For example, in the ordinary jacquard mechanism the open shed is formed by raising certain of the warp ends, while the others remain fixed, thus necessitating 75 the warp being raised, say four inches for a four inch opening, while in our invention for such an opening the warp is raised only two inches at one side of the level and lowered two inches at the opposite side, thereby 80 giving the full four inch opening with a material reduction in the tension upon the warp ends. In other words, the strain upon the warp ends is equalized by lowering a portion of the warp ends, while the other 85 part is raised, and as a result the breakage of the ends is reduced to a minimum.

In view of the fact that the grate or auxiliary griff frame 29 is a movable structure instead of a fixed one as in the ordinary jacquard head, it will be obvious that some means for supporting the needles are necessary since the ordinary support is mounted upon the usual fixed grate. In the present instance, therefore, we have provided a 90 frame 42 which is fixed to the head 1 in a plane removed from the path of movement of the grate or auxiliary griff frame 29, and to this frame there is secured the apertured uprights 43 which serve to support the 95 transverse wires 44 forming braces for the intermediate portion of the needles.

By reference to Fig. 1 it will be seen that each of the needles controls a single hook, and in consequence of the fact that both cylinders are in operative position simultaneously it follows that the two cards controlled by the cylinders are punched so that they act 100 together to form the shed for one pick. In other words, a portion of the pick is punched on one card, and the remaining portion upon the other card, with the result that a simultaneous positioning of the two cards determines the hooks which are to be called up 105 for one pick of the weft. Another result of controlling each hook by a separate needle is that substantially twice the number of needles may be used in the weaving operation, thereby giving a wide latitude of design and further permitting each hook to control but 110

two threads of the harness. This latter tie-up gives the widest possible range in the design of the cloth and the arrangement and variation of the design is only limited by the 5 width of the goods.

By reference to Fig. 1 of the drawings, it will further be noted that the neck cords 45 are connected respectively to the hooks, namely one neck cord to each hook, and in 10 this construction the neck cord is always maintained under tension and is not subject to the frictional wear which is an incident of a neck cord looped and controlled by two hooks, which is the construction employed in the majority of present-day jac- 15 quard machines.

In Fig. 6 we have shown a modified form 20 of upper griff frame wherein 46 designates the frame forming a support for a plurality of V-shaped griffs or knives, so that each V-knife is adapted to govern double the number of hooks controlled by either of the frame parts 15 or 16. In this arrangement one of the frame parts, as 16, may be dis- 25 pensed with entirely since one side of the V-shaped knife 47 corresponds to a knife on the frame part 16 and takes care of the hooks controlled by the knives 26 of the upper griff frame operated thereby. The 30 use of this frame 46 does not vary or change the operation of our invention but contributes to simplification of construction. In other words, the knives 25 and 26 of the upper griff frame may be in one unitary 35 structure.

In Fig. 4 the line *a-a* represents the normal level of the warp ends while the line *b* represents the warp raised by the 40 hooks which are called up, and *c* the warp ends lowered by the movable grate. This 45 illustrates the formation of the shed opening and as here shown the two sets of warp ends move substantially the same distance, one set being distance *a* above the level and the other set distance *a* below the level. Of course, it will be understood that we are not to be limited to this exact proportional movement as obviously the opening may be varied and the relative movements of the 50 griff frame and grate varied.

The operation of the jacquard head is as follows:—As soon as the machine is started the card cylinders 2 and 3 are simultaneously advanced toward the head frame and each presents a card to the respective sets 55 of needles 8. As these cards together determine the hooks which are to be called up for that particular pick of the weft, certain of the hooks, normally supported by each of the frames 15 and 16 moving as a unit, will be removed from the path of movement of the griffs or knives, while those remaining will control the lifting of the required warp end.

65 It will be noted that the aforesaid cyl-

inders 2 and 3 are reciprocated toward and away from the frame 1 through the medium of the cam members 9, which are controlled by the raising and lowering of the arms 11, these latter being actuated by the rocking 70 of the beam 21 and its connections. Since the plunger rod 12 has a fixed connection with the frame 15, and the plunger rod 13 has fixed connection with the frame 16, these two frames, together with the griff 75 knives 25 and 26, will be simultaneously raised and lowered, as a unit and together constituting the upper griff frame, thus bringing up those hooks which remain in the path of the knives, as will be apparent. 80 The reciprocation of the beam 21 in the present instance is also utilized to reciprocate the grate or auxiliary griff frame 29 in such a manner that those hooks 27 which have been removed from the knives are 85 lowered with the grate or auxiliary griff frame 29 at the same time that the upper griff frame structure raises the hooks called up by the cards. The result of this movement is to raise certain of the warp ends and 90 lower the remaining warp ends so that the shed opening is formed of the required size but without undue tension upon the raised ends. In other words the tension upon the warp is equalized and the tendency of the 95 ends to break during the operation of the loom is lessened to such an extent as to be practically negligible. In fact it has been found in practice in the operation of our invention, that the breakage of warp ends 100 is such an inconsiderable factor as to greatly increase the number of looms which can be taken care of by a single operator.

A further and very important feature of our invention resides in utilizing a tie-up for the harness wherein each hook independently controls its neck cord, in consequence of which the wear upon the neck cords is substantially uniform, so that the level of the warp, having been once established initially, remains practically constant throughout the operation of the loom. The resulting product is, therefore, finer in quality, texture and appearance, and entirely free from defective portions caused in the 110 ordinary loom by differences in the level of the warp. These differences in the level, it will be understood, are caused by the unequal stretching of new neck cords with respect to those which have been in use for 115 some time. In our present invention, therefore, it will be apparent that the harness is all practically the same age as distinguished from repaired harness which has new neck cords in place of those worn out by loop- 120 and friction.

It will further be apparent by employing our present tie-up with the harness of each hook passing through holes in the same longitudinal row of comb board, that it is 130

possible to employ all cards interchangeably without rearranging or changing the tie-up with its consequent loss of time.

It will now be apparent that we have devised a novel and useful construction which embodies the features of advantage enumerated as desirable, and while we have in the present instance shown and described the preferred embodiment thereof which has been found in practice to give satisfactory and reliable results, it is to be understood that we do not restrict ourselves to the details, as the same are susceptible of modification in various particulars without departing from the spirit or scope of the invention.

Having thus described our invention, what we claim and desire to protect by Letters Patent is:—

1. In a jacquard mechanism for looms, the combination of a plurality of hooks for controlling the warps, an upper movable griff frame and an auxiliary griff frame each of which is adapted to support all of the hooks, and latter of which is adapted to lower any or all of the hooks, and the former of which is adapted to raise any or all of the hooks, means for moving the two griff frames simultaneously in opposite directions and to substantially the same extent whereby at every reciprocation of said griff frames all of the hooks are operated, certain being raised and the remainder lowered, two reciprocable card cylinders rotatably mounted, two sets of needles respectively controlled by the cylinders and their cards, whereby all of the needles are simultaneously operated, one-half of said needles arranged to control one-half of the hooks, and the other half of the needles arranged to control the remaining half of the hooks, and two sets of cards respectively adapted to the card cylinders.

2. In a jacquard mechanism for looms, the combination of a plurality of hooks for controlling the warps certain of which have hooked ends pointing in one direction and the remainder having hooked ends pointing in the opposite direction, an upper movable griff frame and a lower auxiliary griff frame, each of which is adapted to support all of the hooks and the latter of which is adapted to lower any or all of the hooks, the former of said griff frames having a plurality of blades a portion of which are operatively arranged to act in one direction and the remaining portion in the opposite direction and respectively adapted to engage the oppositely pointed hooked ends of the hooks, means for moving the two griff frames simultaneously in opposite directions and to substantially the same extent whereby at every reciprocation of said griff frames all of the hooks are operated, certain being raised and the remainder lowered, two re-

ciprocable card cylinders rotatably mounted at opposite sides of the hooks and griff frames, two sets of needles respectively controlled by the cylinders and their cards operating in opposite directions and respectively controlling the hooks coöperating with the oppositely arranged griff blades, whereby all of the needles are simultaneously operated, and two sets of cards respectively adapted to the card cylinders, and means for simultaneously reciprocating the card cylinders in opposite directions.

3. In a jacquard mechanism for looms, the combination of a plurality of hooks, a lower auxiliary griff frame adapted to raise and lower all of the hooks, an upper griff frame also adapted to raise and lower all of the hooks, means for reciprocating the griff frames simultaneously in opposite directions, needles and card mechanism for controlling the engagement of the hooks with the upper griff frame, a plurality of warps, and harness for connecting warps in pairs to each of the hooks.

4. In a jacquard mechanism for looms, the combination of a plurality of hooks, a lower auxiliary griff frame adapted to raise and lower all of the hooks, an upper griff frame also adapted to raise and lower all of the hooks, means for reciprocating the griff frames simultaneously in opposite directions, needles and card mechanism for controlling the engagement of the hooks with the upper griff frame, a plurality of warps, a neck cord extending downward from each hook for a distance greater than the maximum distance to which the hooks are raised and lowered, and harness for connecting warps in pairs to each of the hooks through the neck cord.

5. In a jacquard mechanism for looms, the combination of a plurality of hooks, a lower auxiliary griff frame adapted to raise and lower all of the hooks, means for reciprocating the griff frames simultaneously in opposite directions, needles and card mechanism for controlling the engagement of the hooks with the upper griff frame, a plurality of warps, a neck cord extending downward from each hook for a distance greater than the maximum distance to which the hooks are raised and lowered, and harness for connecting widely separated warps in pairs to each of the hooks through the neck cord, whereby the harness cords cross from each warp to the neck cord to make an angle with each other which prevents the cords from excessive contacting.

6. In a jacquard mechanism for looms, the combination of a plurality of hooks, a lower auxiliary griff frame adapted to raise and lower all of the hooks, an upper griff frame also adapted to raise and lower all of the hooks, and harness for connecting warps in pairs to each of the hooks through the neck cord.

of the hooks, means for reciprocating the griff frames simultaneously in opposite directions, needles and card mechanism for controlling the engagement of the hooks 5 with the upper griff frame, a plurality of warps, and harness for connecting pairs of warps separated a distance apart equal to or greater than one half the width of the warp shed in the direction of the width of 10 the fabric, said harness for each pair of warps connected at its top to one of the hooks whereby the harness cords cross each other at considerable angles.

7. In a jacquard mechanism, a griff frame, 15 a plurality of hooks operatively mounted with respect thereto and all of said hooks adapted to be raised thereby, a supporting frame for the hooks separate from the griff frame and also adapted to support all of 20 the hooks, means for simultaneously reciprocating the griff frame and the support for the hooks in opposite directions, and two sets of needles one set arranged to control

one half of the hooks in respect to the griff frame and the other set arranged to control 25 the remaining half of the hooks in respect to the same griff frame, separate card cylinders for each set of needles, means to move the card cylinders simultaneously to operate the needles for controlling all of the hooks, 30 and two sets of cards one set of said cards for controlling the needles for one half of the hooks and their warps and the other set for controlling the needles for the other half of the hooks and their warps, and in which 35 the two sets of cards and their needles control all of the hooks whereby certain of the hooks are raised by the griff frame and the remainder lowered by the supporting frame.

In testimony of which invention, we here- 40 unto set our hands.
